United States Patent Office

Des. 232,267

Patented July 30, 1974

232,267

WRITING INSTRUMENT

Nathan A. Zepell, 1359 Santa Teresita Drive,
Santa Barbara, Calif. 93105

Filed Aug. 18, 1972, Ser. No. 281,920

Term of patent 14 years

Int. Cl. D19—06

U.S. Cl. D74—17 B

FIG. 2.

FIG. 1.

FIG. 3.

FIG. 4.

FIG. 5.

FIG. 1 is a front elevational view of a writing instrument showing my new design, the rear elevational view being substantially identical thereto;

FIG. 2 is a left side elevational view;

FIG. 3 is a right side elevational view;

FIG. 4 is an enlarged scale bottom plan view; and

FIG. 5 is an enlarged scale top plan view.

I claim:

The ornamental design for a writing instrument, as shown and described.
